[57] CLAIM

The ornamental design for an escutcheon, as shown and
 described.

DESCRIPTION

FIG. 1 is a bottom, left, front perspective view of an
 escutcheon showing my new design;

FIG. 2 is a front elevational view thereof;

FIG. 3 is a top plan view thereof;

FIG. 4 is a bottom plan view thereof;

FIG. 5 is a left side elevational view thereof;

FIG. 6 is a right side elevational view thereof;
 FIG. 7 is a cross sectional view taken on line 7—7 of
 FIG. 2; and

FIG. 8 is a front elevational view of a second embodiment
 thereof.

The broken line representation of holes in FIG. 8 is for
 purposes of illustration only and forms no part of the
 claimed design.
